David Bear of Shepherdstown (Virginia)
Letters Patent.

The Schedule referred to in these Letters Patent and making part of the same containing a description in the words of the said David Bear himself of his improvement in the machinery applicable to the raising of water by means of a weight."

To all to whom these presents shall come. To wit known that I, David Bear, of Shepherdstown in the County of Jefferson and State of Virginia have invented a new and useful improvement in the machinery applicable to the raising water by means of a weight acting by an arrangement of wheels upon a lever, connected with the pump rod or upon a chain belt, and elevator; and that the following is a full and exact description of the manner in which the same is to be carried into effect, as being fully described and ascertained in and by the following description thereof, reference being had to the drawing hereto annexed, by the letters marked theron. My invention consists in combining several well known parts in such a manner as to produce an arrangement of machinery applicable to raising water by operation of a weight either with or without a pendulum being attached, also in constructing a balanced lever to work in a toothed wheel as to dispense with said pendulum when desired.

Description of the drawing. That is to say, Fig. 1. is a side view of the machinery arranged according to the invention. Fig. 2. is a plan in both of which figures as well as in several others as sections, the same capital letters of reference indicate the several parts. A. the frame or axle. B. the rope or chain to which the weight is attached and which is wound round the lower barrel C. which is furnished with the hand and ratchet wheel D. to connect it while the weight is exerting its force with the toothed wheel E. in the ordinary way. The pinion E¹ is driven by the main wheel B¹ and has fast upon its axis the toothed wheel G. which works into the pinion H. made fast upon the axis. Though I do purpose in some cases to dispense with the wheel or pinion E¹ & E² and place the pinion H to be driven by the main wheel B¹. On the same axle as the pinion H is placed the escapement wheel I. for the purpose of connecting the pendulum weight and ratchet, in the ordinary way of clock work, when desired.

use that mode of regulating the motion of the wheel. It is a wheel. But I have preferred another method which I prefer as being more simple and advantageous. Thus, by the side of the escapement wheel T. is to be placed the toothed wheel S. having the cog, brought to a sharp edge. and on the top of it is placed the horizontal lever K. turning on its axis in the frame work. at the extreme end of this lever beyond the frame work and where the piston or pump rod M. is to be attached for raising the water by an ordinary Pump. I place the weight A. and at the other end which is to play over the escapement wheel T. also place the weight C. so as to adjust or place in equilibrium the lever on each side of its axis.

This weight is suspended by a hook upon the bent or curved wire P at the lower part thereof. This curved wire rod is secured to the box at Q at one end having the other sufficiently extended to embrace the escapement wheel and touch it at a point opposite to the end of the lever which touches on the same wheel. The end of the wire is here bent up so much as to easily adjust it to chafe by its use against a bottom tooth. The motion allowed by the escape from the lever head of the top tooth on the opposite side and thus alternately regulates the motion of the pinion H in the same direction as will the ordinary escapement usage of Pendulum as already mentioned and this mode of operation. The barrel when all the rope is uncoiled may be wound up again by the application of the pinion R by the crank S. which will be displaced when not in use. I also purpose to adapt a chain bell and elevators T. to the axis of the escapement wheel T. by means of a pulley thereon and one beneath the surface of the water should that mode be preferred to raising the ordinary pump. The size of the wheel and the number of coggs thereon I do not confine myself to as they will evidently be subject to variation according to the speed required or desired. I would also say that the escapement wheel and pinion H. may be secured upon an axis together without the wheel T. in which case when the Pendulum motion is wanted the axle and wheel T. will be removed and one with the escapement substituted for it. It would be understood not to claim any of the various parts used separately but I do claim as my invention the manner in which the Pendulum

adapt the lever K another which I. was to regulate the motion of
the pinion H.
